UNITED STATES PATENT OFFICE.

CARL SCHALLER, OF BRUNSWICK, GERMANY.

CALCULATING-MACHINE.

1,109,471.

Specification of Letters Patent. Patented Sept. 1, 1914.

Application filed January 27, 1914. Serial No. 814,782.

To all whom it may concern:

Be it known that I, CARL SCHALLER, workmaster, citizen of the Duchy of Brunswick, Empire of Germany, residing at Brunswick, Germany, have invented certain new and useful Improvements in Calculating-Machines, of which the following is a specification.

My invention relates to improvements in calculating machines, and more particularly in calculating machines of that class, in which setting members in the form of keys are arranged in columns, the keys of each column coöperating with a registering wheel 10 which is adapted to be rotated by controlling members when depressing a key of the column, the angle of rotation of the wheel corresponding to the value represented by the depressed key.

20 The object of the improvements is to provide a machine of this class in which the mechanism for transmitting the movements of the keys to the registering mechanism is simple in construction and reliable in operation.

25 With this object in view my invention consists in constructing the said controlling members in such a way, that they are shifted in the direction of the shaft of the registering wheels, and the shifted and non-shifted members form positive guiding means for a tooth associated with the registering wheel for coupling the same to the driving mechanism.

30 For the purpose of explaining the invention an example embodying the same has been shown in the accompanying drawings, in which the same letters of reference have been used in all the views to indicate corresponding parts.

35 In said drawings Figure 1, is a longitudinal section of the machine, Fig. 2, is a detail view showing the lower part of a shiftable key and the controlling members of one column in normal or inoperative positions, Fig. 3, is a development of the parts of the said controlling members adjacent to the registering wheel with some of the said members in operative and the other ones in inoperative positions, Fig. 4, is a view similar to that shown in Fig. 2 showing the controlling members in operative and the key in locked positions, Fig. 5, is a sectional view of one of the registering wheels, Fig. 6, is 40 a front view of one of the registering wheels, and Fig. 7, is a plan view of two adjacent

registering wheels. Fig. 8, is a partial front view of the registering mechanisms.

In the example illustrated in the drawings, my improved machine consists of a 45 casing 2 the cover plate 2' of which is inclined downward and forward. The cover plate is formed with slots 1' one for each of the stems 1 of the keys, and the stems are arranged in several longitudinal columns 60 disposed one beside the other and each comprising nine keys representing the numbers from 1 to 9. Each stem is formed at its side with teeth 3 the number of which corresponds to the value represented by each 65 key, and which are disposed equal distances apart. At the sides of the keys of each column nine longitudinal bars 4 are located, which are parallel to each other and have 70 rocking supports on a vertical shaft 5. The 75 distance of the said bars is equal to the pitch of the teeth formed on the vertical key stems 1, and the operative faces of the teeth are beveled, so that when depressing in a column for example the key which represents the 80 value "nine" all the nine bars 4 are rocked sidewise, and when depressing the key corresponding to the value "five" only the five upper bars are rocked sidewise. When releasing the key which has been depressed, 85 the bars 4 are returned into normal positions by springs 6, and the keys are shifted upward and into normal positions by springs 7. The keys which are depressed are adapted to be locked in depressed positions by means of rocking bars 8 provided 90 one for each column and having noses 8' adapted to engage lateral shoulders 9 provided at the lower ends of the stems, and in order to release the keys the said bars 95 are rocked out of engagement with the said shoulders. Such rocking movement may be imparted to the bars 8 by any suitable means such for example as a resetting key 48 provided one for each column or one for all the 100 columns, and which acts for example on the rock shafts 8' carrying the rocking bars 8. While in the drawings a rocking bar is shown which is adapted to be rocked into or out of locking engagement with the stems, 105 I wish it to be understood, that my invention is not limited to this feature and that the said locking member may be constructed in a different way.

At the front end of each of the longitudinal bars 4 a head 10 is provided, the heads of the nine bars coöperating to form

in the normal or inoperative positions of the bars a continuous sectional ring, as is shown in Fig. 1. The development of the said ring seen from the front side of the machine is shown in Fig. 3, from which it appears that the first or uppermost head 10' is in the form of a trapezoid, while the other eight heads are in the form of rhomboids. The trapezoidal head of the uppermost bar 4 is actuated by the stems of all the keys, so that it is moved whenever a key is depressed. By depressing one of the keys one or more of the heads 10 is rocked to the side and in any case all the rocked heads form a continuous row which begins with the head 10', as is clearly shown in Fig. 3, wherein the first three heads are represented as shifted to the side, which has been effected by depressing the key representing the value "3". The nine heads 10 and 10' form members for controlling members for a shifting tooth 11 which forms a part of the registering mechanism and revolves about a shaft 12 adapted to be rotated by suitable means such for example as a crank 50 (Fig. 8). In the normal or inoperative position of the bars 4 the said tooth moves along the sectional ring provided by the heads of the bars without engaging the same. However, if one of the keys of the column has been depressed so as to shift a corresponding number of consecutive heads, the revolving tooth is first caused to engage the beveled front face of the first head 10', so that it is shifted laterally and into the position shown in dotted lines in Fig. 3. In this position the tooth 11 engages in teeth 13 of a numeral wheel 14 so as to rotate the same. The said numeral wheel is provided about its circumference with one or more series of the numbers from 1 to 9 and the zero sign. The number of heads which have thus been shifted into operative positions corresponds to the value of the depressed key, and this value is transmitted to the numeral wheel by advancing the same a corresponding number of teeth 13. When the said tooth strikes against the first one of the non-shifted heads it is shifted by the same backward and into inoperative position in which it is out of engagement with the teeth 13, as is likewise shown in dotted lines in Fig. 3. In front of the first head 10' and at the rear of the last head 10 fixed members 43 and 44 may be arranged which are formed with beveled faces corresponding to the beveled faces of the adjacent heads and which provide positive guiding means for the tooth 11 for rocking the same into or out of operative position, as will readily be understood from an inspection of Fig. 3. If desired a spring 49 (Fig. 5) may be connected with the tooth 11 to pull the latter along the beveled face of

the last one of the rocked heads thereby assisting in shifting said tooth into inoperative position. This spring will also serve to hold the tooth in inoperative position relatively to the teeth 13 after moving out of engagement with the rocked heads. 70

As shown in the drawings locking means are provided for locking the numeral wheels 14 which are otherwise loosely mounted on the shaft 12, which locking means release the numeral wheels while being engaged by the teeth 11. As shown such locking means consist of levers 16 having rocking supports at points intermediate their ends on relatively fixed parts 17 of the frame of the machine and on pivots 18 disposed transversely of the shaft 12. The outer ends of the said levers engage between noses 19 on the numeral wheels so as to lock the same against rotation, and the inner ends of the levers are in engagement with sleeves 20 which are shiftable on the shaft 12 and formed with annular grooves 21. The latter are engaged by extensions 23 of the shifting teeth 11, so that when the said teeth are being rocked in one direction the sleeves 20 are shifted axially so as to rock the levers 16, the arrangement being such, that when shifting a tooth 11 into engagement with a numeral wheel 13 the lever 16 is disengaged from the noses 19, and vice versa. 95

In my improved machine carrying means are provided as follows: Each of the numeral wheels 14 is provided on its left hand face with four equidistantly-spaced pins or other stops 33 corresponding to the number of the series of figures from 0 to 9 provided on the numeral wheels. In Fig. 5 the said stops are not shown. When the number 9 of one of such series, followed by 0, or vice versa, passes hole 34, the corresponding pin 33 engages a beveled cam face 35 of a rocking lever 36 mounted on a fixed pivot bolt 37 which is disposed parallel to the shaft 12 of the registering mechanism and on the opposite side of the said shaft from the heads 10. When the pin 33 engages the cam face 35 a beveled, lateral projection 38 on the opposite end of the lever 36 is rocked into the path of a carrying lever 39. The said lever 39 is mounted on a disk 46 which cooperates with the numeral wheel 14 of the next higher order and takes part in the rotation of the shaft 12. For right and left hand operation of the numeral wheel two levers 39 are provided, both of which have rocking supports respectively on pivots 40 which are disposed transversely of shaft 12, in a manner similar to that described with reference to tooth 11, except however that the levers do not project so far outward. The inner ends of the carrying levers 39 engage in the annular groove 21 of the sleeve 20, so that when 130

rocking one of the levers 39 sidewise the shifting tooth 11 is rocked into engagement with the teeth 13 provided on the numeral wheel 14 so as to carry the same along. The 5 length of the beveled part 38 corresponds to the distance between two consecutive digits provided on the numeral wheels, so that the numeral wheel is shifted forward or backward a distance corresponding to one step, 10 as is necessary in the carrying operation.

In order that the lever 39 may be positively shifted not only into but also out of operative position, fixed beveled cam members may be provided at the front and rear sides 15 of the beveled end 38 of the lever 36 which members coöperate with the said end to form guides for the lever 39. At the rear of the lever 39 cams 42 are provided by means of which the beveled end 38 of the 20 lever 36 is rocked backward, and the opposite end 35 is returned into the path of the pins 33, so that the parts are again in operative positions for performing the next carrying operation. The two cams 42 of a 25 numeral wheel 14 may be replaced by a single member.

The several levers 39 of the registering wheels are arranged relatively to one another in the form of a spiral series, as is 30 known in carrying mechanisms.

Indicating means may be provided for displaying through a peep hole, the numbers corresponding to the keys depressed, and in the example shown there is provided 35 for each column of keys a numeral wheel 24, all the said numeral wheels being loosely mounted on a common shaft 25 and in such positions, that when rotating the same the figures provided on the circumferences are 40 successively displayed through peep holes 26 made in the cover 2' of the casing. Each of the numeral wheels has secured to it a pulley 27, or the like, which is connected by a cord or equivalent flexible element 29 with 45 a second pulley 28, or the like.

To the cord the free end of a lever 31 is connected which has a rocking support on a fixed pivot 30 and which is adapted to be depressed by stop members 32 connected one 50 with each of the key stems of each column. The distance of the keys from the pivot corresponds to the value of the keys, so that the lever 31 is rocked by the keys of the column at different angles, though all the 55 keys are depressed the same distance. The rocking movement is transmitted through the cord 29 to the indicating wheel 24 which is rotated thereby. Means are provided for returning the lever 31 and the indicating 60 wheel into initial positions when the depressed key is released and returns into normal position. Such means consist for example of a spring 31'.

The indicating members 24 are not necessarily in the form of wheels, but in lieu

thereof sectors may be provided which are equipped with figures and which are adapted to be rocked from the levers 31 through the agency of suitable connections.

The registering mechanism is disposed on 70 a carriage 43 which is slideable in a direction parallel to the shaft 12 of the numeral wheels. On the said carriage a second registering mechanism 51 (Fig. 8) may be provided for counting the number of revolutions of the shaft 12. As is known in the art revolutions counting mechanisms of this class are ordinarily operated by means of a single tooth wheel 52 which is mounted on or operatively connected with the crank 80 shaft 12. If desired it may be mounted on a relatively fixed part of the machine. It may be provided with carrying mechanism of any known or preferred form.

53 is a zero resetting shaft.

Each of the columns of keys may be provided with locking means in order to prevent several keys of the same column from being simultaneously depressed. Such means are known in the art and need no description.

The mechanism for locking all the keys or all the keys of one column in depressed position may be operatively connected with the driving shaft 12 in such a way, that at 95 the end of its rotation the said shaft unlocks the keys by suitable means such for example as an-unlocking cam which is adapted to rock the locking member or members 8.

The driving members 10, 10' which as shown are disposed in the plane of the numeral wheels and are rocked out of the said plane when depressing a key, may also be disposed at the sides of the numeral wheels 105 14 and shifted when depressing a key toward the numeral wheels so far, that they shift the tooth 11 into position for engagement with the teeth 13.

If desired means may be provided for 110 locking the carriage in correct position, such as are described for example in German Patent No. 123134. For this purpose on the shaft 12 of the registering mechanism a notched disk may be mounted which is 115 adapted to engage in notches formed in the base plate of the machine.

I claim herein as my invention:

1. In a calculating machine, the combination with a rotary registering member, operating means therefor, normally inoperative means for coupling said registering member and operating means, and setting members coöperating with the registering member, of controlling members operated 120 by the setting members extending to points adjacent to the coupling means and adapted to be shifted by said setting members perpendicularly to the direction of movement 125 of the registering member and into position 130

- for throwing said coupling means into coupling position, and means to return the setting members and controlling members into normal positions.
5. 2. In a calculating machine, the combination with a rotary registering member, operating means therefor, normally inoperative means for coupling said registering member and operating means, and setting 10 members coöperating with the registering member, of controlling members operated by the setting members extending to points adjacent to the coupling means and adapted to be shifted by said setting members per- 15 pendicularly to the direction of movement of the registering member and into position for throwing said coupling means into coupling position, the working portions of said controlling members abutting one another and forming a continuous guide way for 20 the coupling means, the abutting faces of said portions being beveled so as to form, when said members are shifted, means for guiding the said coupling means into or out 25 of operative positions, and means to return the setting members and controlling members into normal positions.
3. In a calculating machine, the combination with a rotary registering member, operating 30 means therefor, normally inoperative means for coupling said registering member and operating means, and setting members coöperating with the registering member, of controlling members operated 35 by the setting members extending to points adjacent to the coupling means and adapted to be shifted by said setting members perpendicularly to the direction of movement of the registering member and into 40 position for throwing said coupling means into operative position, the working portions of said controlling members abutting one another and forming a continuous guide way for the coupling means, the abutting 45 faces of said portions being beveled so as to form, when said members are shifted, means for guiding said coupling means into or out of operative positions, stationary guide members provided at the front and rear ends of 50 the said continuous guide way and formed
- with correspondingly beveled faces providing means for guiding said coupling means into or out of operative positions, and means to return the setting members and controlling members into normal positions. 55
4. In a calculating machine, the combination with a registering wheel, a shaft loosely supporting the same, and operating means for the registering wheel, of a coupling member for said registering wheel adapted to connect the same with the operating means, and means controlled by said coupling member for locking the wheel against rotation with the shaft. 60
5. In a calculating machine, the combination with a registering wheel, a shaft loosely supporting the same, and operating means for the registering wheel, of a coupling member for said registering wheel adapted to connect the same with the operating means, a member mounted on a relatively fixed part and adapted to be rocked into engagement with the registering wheel to lock the latter against rotation with said shaft, and a sleeve longitudinally slideable 70 on said shaft and engaged by said coupling member and locking member for transmitting rocking movement from said coupling member to said locking member. 75
6. In a calculating machine, the combination with at least two adjacent registering members of different order, of a rocking member mounted on a relatively fixed part and adapted to be rocked by the registering member of lower order, operating 80 means for the registering members, a coupling member adapted to couple said operating means and registering members and disposed in position for being thrown by said rocking member into coupling position, 85 and means to retract said coupling member into non-coupling position. 90

In testimony whereof I have hereunto set my hand in presence of two subscribing witnesses.

CARL SCHALLER.
